PULLING DEVICE

Frank Sommer, Winnipeg, Manitoba, Canada
Application October 2, 1956, Serial No. 613,576

1 Claim. (Cl. 29—261)

My invention relates to new and useful improvements in pulling devices, specifically pulling devices adapted for use with pulleys, gears, ball races and the like, the specific object and essence of my invention being to provide a device of the character herewithin described which includes a cross-head and parallel action links depending therefrom connected to the jaws and means to move the jaws inwardly and outwardly, the jaws remaining or travelling parallel to the one another at all times.

A further object of my invention is to provide a device of the character herewithin described in which the spaced position of the jaws is maintained mechanically and rigidly.

Yet another object of my invention is to provide a device of the character herewithin described which is adapted to receive various jaws designed for specific pulling functions, said jaws being easily inter-changed as desired.

A still further object of my invention is to provide a device of the character herewithin described which is provided with an attachment adapted to pull Woodruff keys from key ways.

With the foregoing objects in view and such other objects and advantages as will become apparent to those skilled in the art to which this invention relates as this specification proceeds, my invention consists essentially in the arrangement and construction of parts all as hereinafter more particularly described, reference being had to the accompanying drawings in which:

Figure 1 is a front elevation of my device sectioned in part to show the interior thereof.

Figure 2 is a view substantially at right angles to Figure 1.

Figure 3 is a fragmentary front elevation of one of the jaw carrying blocks showing one variation of the jaws attached thereto.

Figure 4 is a view substantially at right angles to Figure 3, but with the parallel motion links not shown.

Figure 5 is a perspective view of one of the alternate jaws per se.

Figure 6 is a side elevation of the attachment for withdrawing keys from key ways.

Figure 7 is a top plan of Figure 6, but with the key and key way not illustrated.

Figure 8 is a perspective view of an alternate jaw construction.

In the drawings like characters of reference indicate corresponding parts in the different figures.

Convention gear and wheel pullers normally consist of links pivotally attached to a cross-head, said links travelling in and out in order to vary the spacing therebetween. This means that the jaw extremities or gripping portions are only in the optimum position for maximum grip at one point of adjustment due to the excessive arc travelled by the jaws with this form of mounting. I have provided parallel link action which not only increases considerably the radius of the arc travelled by the jaws, but also maintains the jaw stem vertical

2

and parallel at all times with the adjustment and therefore maintains the engaging portions of the jaws at the same angle with the horizontal at all times. Furthermore, the adjustment of the jaw widths is mechanical and is fixed rigidly when in position.

Proceeding now to describe my invention in detail, it will be seen upon reference to Figures 1 and 2 that it consists of a cross-head 1 centrally apertured as at 2 and having a hub 3 defining the aperture and depending from the cross-head 1 being strengthened by fins 4. Although in this embodiment the cross-head is substantially rectangular when viewed in plan, nevertheless it will be appreciated that if more than two pulling jaws are incorporated than this cross-head could be circular or any other convenient configuration.

Upon each side 5 of the cross-head I have provided a set of parallel motion links collectively designated 6, each set consisting of an inner pair of links 7 and an outer pair of links 8. Each of these pairs are pivotally connected by the upper ends thereof to the cross-head 1 by means of pivot bolts 9 and the inner and outer pairs of each set depend in parallel relationship from the cross-head.

The lower ends 10 of the four pairs of links 7 and 8, are in turn pivotally connected to jaw locks 11 by means of pivot bolt 12 so that it will be appreciated that the jaw block 12 can be pivoted in an arc of relatively large radius, but the vertical faces 13 thereof remain vertical and parallel with one another at all times due to the parallel motion links hereinbefore described.

A parallel motion component collectively designated 14 consists of an adjustment wheel 15 situated above the cross-head 1 and having a cylinder 16 screw-threaded to and depending therefrom, and secured by means of set screws, said cylinder being journaled for rotation within the aforementioned central aperture 2 of the cross-head.

The lower end 18 of the cylinder 16 is shouldered and screw-threaded externally being engageable by a collar 19 which is also screw-threaded, said collar having lug 20 extending outwardly therefrom. To each of these lugs 20 is secured a pair of parallel motion actuating links 21 by means of pivot bolts 22 and these links extend downwardly and outwardly to be connected by the lower ends 23 thereof to the aforementioned pivot bolts 12 holding the outer pairs of parallel motion links 8 to the blocks 11, as clearly illustrated. This shoulder bears against the underside of hub 3 and this together with the attachment of wheel 15 permits the wheel 15 and cylinder 16 to be rotated freely within the aperture 2, but prevents vertical movement from occurring of the said wheel and cylinder.

From the foregoing it will be appreciated that rotation of the wheel 15 will cause the sleeve or collar 19 to move vertically upon the cylinder 16 and thus due to the connecting links 21, will open and close the jaw blocks 11 maintaining same vertical and parallel to one another at all times.

Before leaving the description of the actuating component, it will be noticed that the cylinder and wheel are apertured centrally and screw-threaded internally to receive the conventional pressure rod 24 which is screw-threaded externally and extends downwardly between the jaw blocks 11, being provided with an apertured boss 25 on the upper end thereof to receive an actuating rod (not illustrated) and a hardened tip 26 in the lower end thereof to engage the shaft or similar component from which the wheel pulley or gear is being drawn.

The jaw blocks 11 are apertured horizontally as at 27 to receive bolts 28 which in turn engage jaws 29 illustrated in Figures 1 and 2. These jaws consist of

an attaching portion 30 engageable by the bolts 28, vertical stem portion 31 extending downwardly from the attaching portions 30 and jaw portions 32 formed on the lower end of the stem 31. In the embodiments shown in Figures 1 and 2, these jaw portions 32 turn outwardly from the stem portion 31 and are provided with curved ends 33 adapted to engage within an annular groove of a ball race cage or the like. However, Figures 3 and 4 show alternative embodiments of these jaw portions 33 which consist of flat plates 34 secured to the undersides 35 of the stem portion 31 by means of bolt 36. These jaw portions can be used for internal or external pulling and consist of a flange portion 36 and curved sides 37 for engagement within or under the article being pulled.

For straightforward gear and pulley removal, jaws such as illustrated in Figure 5 may be utilized. These also include an attaching portion 30, a stem portion 31, and turned sharpened jaw portions 38 which may also be used internally or externally. In this connection, bolts 28 would engage screw-threaded apertures 39 within the attaching portions 30.

Figure 8 shows a combination jaw block and jaw portion assembly including the jaw block 40 and jaw portion 41 formed on the lower side thereof. This jaw block is adapted to be fitted in place of the jaw blocks 11 and connected directly to the lower ends 10 of the set of links 7 and 8 and the jaw portion 41 is provided with an inwardly extending flange 42 having a concave sharpened edge 43. These jaws are adapted specifically to engage under a ball or roller race pressed against a flat surface and the wedge shaped configuration of the edge 43 facilitates the engagement under the ball race and subsequent withdrawal thereof.

My device is specifically designed also for the withdrawal of keys from key ways and reference to Figures 6 and 7 will show that I have utilized a pair of extension stems 50 adapted to be secured to the jaw blocks 11 by means of bolt 28 in a way similar to the attachment of the jaws 29. The opposite ends 51 of the stems 50 are adapted to receive the mounting block 52 therebetween, said mounting block being secured by means of bolts 53, passing through the ends 51 of the stem. Upon one side of the mounting block I provide a single hook jaw 54 being secured by means of bolts 55 and extending forwardly from the mounting block 52. This hook jaw is adapted to engage the key 55 and actuation of the device will withdraw the key from the key way 56, pressure rod 24 engaging the end of the shaft in the usual manner.

In operation, the required jaw assemblies are secured to the jaw blocks 11 or in the case of the assembly shown in Figures 8, the assembly is substituted for the jaw blocks 11. The jaws are then offered up to the article to be withdrawn and wheel 15 is rotated so that the jaws engage the article being withdrawn in the conventional manner. In this connection, it should again be stressed that actuation of wheel 15 causes the jaws to move outwardly or inwardly as desired, but that the vertical surfaces 49 of the jaws always remain parallel with one another irrespective of their position. Once

the jaws are locked in position, the pressure bar 24 is rotated and operated in the conventional manner thus withdrawing the article from its retaining shaft or the like.

Finally, it will be noticed that I have provided a handle 57 extending outwardly from the hub 3 of the cross-head, said handle being provided for steadyng purposes. In this connection, the stem 58 of the handle engages the hub 3 screw-threadably and the innermost end of this stem is designed to act as the aforementioned pin engageable with the groove 2 of the cylinder 16.

Since various modifications can be made in my invention as hereinabove described, and many apparently widely different embodiments of same made within the spirit and scope of the claim without departing from such spirit and scope, it is intended that all matter contained in the accompanying specification shall be interpreted as illustrative only and not in a limiting sense.

What I claim as my invention is:

In a pulling device, the combination of a cross-head provided with a central aperture, an internally screw-threaded substantially tubular member rotatably journaled in said aperture and having an externally screw-threaded portion below said cross-head, means connected to said tubular member above the cross-head for rotating the same, a screw-threaded pressure exerting rod extending axially through said tubular member and operatively engaging the internal screw-thread thereof, pairs of parallel inner and outer links disposed at opposite sides of said rod and pivoted at their upper ends to opposite sides of said cross-head, a pair of jaw supporting blocks provided with transverse bores, inner and outer pivot elements connecting the lower ends of the respective inner and outer links to said blocks, parallel work engaging jaws, fastening elements extending through the bores in said blocks and into threaded apertures provided in said jaws whereby the jaws are removably secured to said blocks, an internally screw-threaded collar positioned on and operatively engaging said externally screw-threaded portion of said tubular member, and pairs of connecting links pivoted at their upper ends to said collar at points spaced inwardly from the inner pair of parallel links, the lower ends of said connecting links being pivoted by said outer pivot elements to said blocks, whereby during rotation of said tubular member in said cross-head said blocks may be moved toward and away from each other while maintaining said work engaging jaws thereon in parallel relation.
